UNITED STATES PATENT OFFICE.

CONRAD M. SCHANZ, OF CHELSEA, MICHIGAN.

NECK-YOKE FASTENER.

SPECIFICATION forming part of Letters Patent No. 694,202, dated February 25, 1902.

Application filed October 1, 1901. Serial No. 77,251. (No model.)

To all whom it may concern:

Be it known that I, CONRAD M. SCHANZ, a citizen of the United States, residing at Chelsea, in the county of Washtenaw and State of Michigan, have invented certain new and useful Improvements in Automatic Neck-Yoke Fastenings, of which the following is a specification, reference being had therein to the accompanying drawings.

This invention relates to an improved neck-yoke coupling for wagon-tongues or carriage-poles, the object being to provide a neck-yoke fastener which can be produced at the minimum of cost, which shall have no springs or small fragile parts incident to it, which can be readily applied to any tongue or pole now ordinarily constructed, and which shall offer no breakable projecting parts that will be endangered when the pole drops to or moves along the ground in either direction.

Figure 1 is a side elevation of a sufficient portion of a wagon-tongue, illustrating the manner of applying my improved neck-yoke fastener. Fig. 2 is a bottom view thereof. Fig. 3 shows the parts in the positions occupied when the neck-yoke ring is to be released.

In the drawings, A indicates the tongue or pole of a vehicle secured to the latter in any ordinary or suitable way, projecting forward therefrom. This is ordinarily formed of wood and generally tapers from the rear end toward the front.

B represents the neck-yoke, which is connected in the usual manner to the harness of the horses and is provided with a ring C at its center that is loosely connected to the tongue.

When the parts are in position and the horses are attached, the tongue is frequently subjected to violent movements in various directions, and these whippings or jarrings are transmitted to the ring C, and unless proper provision is made there is liability of accidental detachment of the latter. It is desirable to overcome this and at the same time allow for an instantaneous removal of the ring C from the tongue when necessary.

To guard against the escape of the ring forward—that is, by movement outward on the tongue—I employ the automatically-acting lock D, and to prevent it from slipping

too far backward I employ a stop formed upon the part (indicated as a whole by E) which serves to reinforce the tongue at the front end and prevent its breakage and relieve it from wear and cutting, the said part which prevents the backward slipping of the yoke-ring C being indicated by E'. The part D comprises the stop-finger proper, d, the inclined carrying-arm d', the hinging part d'', and the stop-lug d''. This front stop device for the ring is so constructed and arranged as to obviate entirely the necessity of springs or any supplemental parts for insuring its normally remaining in an operative position, the hinging part at d'' being thrown as far forward as possible, and the stop-finger d is made heavy and being at the extreme end of the inclined arm d' tends to drop into its operative position at all times to prevent the escape of the ring. This can be applied to any of the ordinary tongues or poles, merely requiring the boring of a small hole upward from the under side of the tongue, which can be accomplished under almost any ordinary circumstances, it requiring no special tools.

In most of the neck-yoke holders which are at all similar to mine with which I am acquainted either the entire front stop has been of the nature of a spring, being formed of elastic metal throughout and requiring the cutting away of a large part of the wood of the tongue or pole, or else has been so constructed and arranged that supplemental spring parts are necessary for the insuring of the proper holding of the stop in the position where it would prevent accidental displacement of the ring.

The part E above referred to has the upper concavo-convex plate e, the lower plate e' fitted to the curved top and bottom surfaces of the tongue, and has also a strong curved front loop e'' and the downwardly-turned stop-loop E', these parts e, e', e'', and E' all being made integral. The loop part e'' at the front is of thick heavy metal, capable of standing much strain from jars and shocks, and it is to this that I hinge or pivot the stop device C; but to relieve the hinging devices of too severe blows or shocks I pass the stop-finger d up through an aperture at e'' in the bottom guard-plate e' and adjust the parts so that the pin or arm d will bear against the for-

ward wall of this aperture, and thus provide the pin or finger d and its carrier d' d^2 with an abutment which takes the strain at the most advantageous point—to wit, at the end 5 of the finger.

By examining Fig. 1 it will be seen that the ring is held between the front stop e and the rear stop E' , and that as the latter never requires any movement it can be formed at 10 once by properly bending the bracing or guarding plate e' .

To hold the pin or finger d in proper position and prevent its upper end from escaping from the aperture e^3 in the plate e' and from 15 the socket a in the tongue, I provide the holder, which is preferably integral with the arm d' and so related to the other parts as to impinge against the loop e^2 when the pin or finger is in the operating position.

20 When it is desired to remove the neck-yoke and its ring from the tongue, it is merely necessary to push up on the finger d or arm d' or pull down on the stop-arm d^3 , this action carrying the stop-finger up far enough to permit 25 the ring to pass over it. When springs of any efficiency are employed, they require considerable power to elevate the stop part against their resistance, and, moreover, are constantly liable to be broken and to become 30 clogged with soil and foreign materials, and inasmuch as the heavy wagons, ditching-machines, excavating-machines, and the like to which this invention is particularly adapted are apt when in use to be at a distance from 35 blacksmith or other repair shops much inconvenience is incident to the use of devices which depend upon elastic holders. My improved front stop D can be readily applied to tongues having guarding and bracing parts 40 substantially similar to that at D , there being merely required the forming of a hinge-pin aperture d^2 , the small socket a in the wood, and the aperture e^2 in the plate e' .

What I claim is—

1. A neck-yoke fastener having in combination with the tongue A and the bracing and guard part E , with the upper and lower plates e e' , the front loop e^2 and the stop-loop E' , the gravity-actuated front stop formed with the upwardly-extending finger d , and the arm d' hinged to the front loop e^2 and extending rearward therefrom, said finger d being normally held with its free upper end in the aperture e^3 in plate e' , substantially as set forth. 45

2. A device for strengthening the front end 55 of a vehicle-pole and fastening a neck-yoke thereto, having the bracing and guard part E formed of the upper and lower plates e e' joined by the front loop e^2 , the lower plate e' being bent down to form the back stop-loop E' , 60 and said plate e' having an aperture e^3 in front of the loop E' , the swinging arm d' hinged to the front loop e^2 , the stop-arm d^3 engaging with said loop, and the stop-pin d normally held by said arm d' with its upper end in the 65 aperture e^3 , substantially as set forth.

3. In a neck-yoke fastener, the combination of a plate adapted to be fitted on the vehicle-pole, having a downward projection to hold the harness-ring from backward movement 70 and formed with the aperture e^3 , a stop-arm for holding said ring from forward movement, said arm being hinged at its forward end to the plate to move toward and from the same, and having a rear finger extending toward 75 the plate and into said aperture, and means for holding the end of the finger within the aperture when the finger is in operative position to retain the harness-ring.

In testimony whereof I affix my signature 80 in presence of two witnesses.

CONRAD M. SCHANZ.
